UNITED STATES PATENT OFFICE.

FRANCIS WRIGHT, OF LUTON, ENGLAND.

STRAW HAT.

1,082,060.

Specification of Letters Patent. Patented Dec. 23, 1913.

Application filed January 9, 1913. Serial No. 740,978.

To all whom it may concern:

Be it known that I, FRANCIS WRIGHT, a subject of the King of Great Britain, residing at 23rd Cardiff road, Luton, in the county of Bedford, England, have invented certain new and useful Improvements in or Relating to Straw Hats, of which the following is a specification.

This invention relates to straw hats whereof the brim and side portions of the crown are unstiffened so as to render them soft and pliable, the object of the present invention being to preserve the flexibility of the parts while enabling the hat to conform to the head of the wearer and to retain its shape in wear.

According to this invention a suitable number of radially arranged flexible but inextensible bands are provided in the brim and extended up to a certain distance into the interior of the crown portion; the said bands having their ends secured to the latter portion after being passed around the strip of straw covered cane which is inserted at the outer circumference of the brim between the layers comprising the same. In conjunction with the aforesaid radial bands a band of the inextensible material is applied in a taut condition about the outer side of the crown portion near the brim. It has heretofore been proposed to apply insertion strips composed of metal shaped to the angle formed by the junction of the brim and crown portions but these arrangements do not afford the effect aimed at by the present invention.

In order that the said invention may be clearly understood and readily carried into effect, I will proceed to describe the same with reference to the accompanying drawings, in which:

Figure 1 is a perspective view of a hat constructed according to the present invention. Fig. 2 is a plan of the under side of the brim looking into the interior of the crown portion, and having fragments of the under brim broken away so as to expose the radial bands. Fig. 3 is a diagrammatic view in section of the crown and brim portions of the hat drawn to a larger scale.

The brim *a* and the sides *b* of the crown portion are not treated for stiffening as is the case with ordinary straw hats, the principal object being to render the hat soft and pliable so that the same will accommodate itself to the shape of the head and afford

ease and comfort to the wearer. In order to enable the said parts to preserve their shape while not detracting from the soft and pliable nature of the article, a suitable number of radially disposed bands *c* are fitted into the brim *a* and their ends secured in the interior of the crown portion *b*. These bands are formed of webbing or some similar material which is practically inextensible so that when they are secured in a taut condition in the brim and crown portions the length of the said bands will not be subjected to variation. The bands *c* are applied by passing the same about the straw covered cane edging *d*, the cane therein being indicated at *d'*. This edging is usually inserted between the upper and under brim parts and is secured in the ordinary way. The said bands *c* are drawn taut across the brim and the ends are carried a certain distance up the inner side of the crown portion (as shown at Fig. 3) to which latter the said ends are secured by stitching or other suitable means. In conjunction with the aforesaid bands *c* a band *e* of the said inextensible material is also applied around the exterior surface of the crown *b*. This band is secured by stitching or other convenient means after the same has been drawn tightly and closely about the outer surface of the crown.

The above described arrangement affords an effective and economical method of securing a perfectly flexible and soft fitting straw hat, the latter conforming readily to the shape or conformation of the wearer's head and owing to the inextensible character of the surrounding band and the intervening radial bands the size and shape of the hat and brim generally are preserved. The bands do not detract from the pliability of the crown portion and brim although they have a restraining influence owing to their inability to stretch or lengthen.

What I claim and desire to secure by Letters Patent of the United States is:

1. In a straw hat, the combination with unstiffened brim and crown portions of flexible but inextensible bands of woven fabric each secured in taut condition radially in the brim and having a part which extends up and is secured to the inner side of the crown portion and a band of inextensible material which is bound tightly around the outer surface of the crown portion so as to be operative at the lower part thereof near

the angle formed by the junction of the brim therewith.

2. In a straw hat, the combination with unstiffened brim and crown portions of flexible but inextensible bands composed of webbing which are secured in taut condition radially in the brim and which extend up and are secured to the inner side of the crown portion and a band of webbing which is bound tightly around the outer surface of the crown portion so as to be operative at the lower part thereof near the angle formed by the junction of the brim therewith.

3. In a straw hat, the combination with unstiffened brim and crown portions of flexible but inextensible bands composed of webbing which are secured in taut condi-

tion radially in the brim by passing the said bands about the straw covered cane strip insertion and between the upper and under 20 brims and which bands extend up and are secured to the inner side of the crown portion and a band of webbing which is bound tightly around the outer surface of the crown portion so as to be operative at the lower 25 part thereof near the angle formed by the junction of the brim therewith.

In testimony whereof I affix my signature in presence of two witnesses.

FRANCIS WRIGHT.
